UNITED STATES PATENT OFFICE.

CHARLES A. HUTTINGER, OF LAKewood, OHIO, ASSIGNOR TO THE ACME ARTIFICIAL SILK COMPANY, OF CLEVELAND, OHIO, A CORPORATION OF OHIO.

BOBBIN-WINDING MECHANISM AND SPEED CONTROL THEREFOR.

Original application filed October 9, 1919, Serial No. 329,471. Divided and this application filed May 24, 1922. Serial No. 563,405.

To all whom it may concern:

Be it known that I, CHARLES A. HUTTINGER, a citizen of the United States, resident of Lakewood, county of Cuyahoga, 5 and State of Ohio, have invented new and useful Improvements in Bobbin-Winding Mechanism and Speed Controls Therefor, of which the following is a specification, the principle of the invention being herein explained and the best mode in which I have contemplated applying that principle, so as to 10 distinguish it from other inventions.

The subject matter of this application has been divided out of my pending application, 15 Serial No. 329,471, filed October 9, 1919.

My invention relates to bobbin winding mechanism and speed control therefor and particularly to apparatus of this character utilized for winding upon bobbins artificial 20 silk such as viscose threads. Particularly, my invention relates to means in apparatus of this character in which the thread is subjected to a minimum amount of friction when being wound.

25 The annexed drawings and the following description set forth in detail certain means embodying my invention, the disclosed means, however, constituting but one of the various mechanical forms in which the principle of the invention may be employed.

In said annexed drawings:

Figure 1 represents a plan view of a fragmentary portion of my machine;

Figure 2 represents, upon an enlarged scale, a vertical longitudinal section, taken in the plane indicated by the lines II—II, Figures 1 and 4;

Figure 3 represents a transverse vertical section taken in the plane indicated by the line III—III, Figure 2;

Figure 4 represents a fragmentary side elevation; and

Figure 5 represents a fragmentary end elevation.

Referring to the annexed drawings, a plurality of pairs of shafts 1 and 2 are mounted in a suitable frame, each pair of shafts, in the manner hereinafter fully described, forming part of the means for rotating by frictional rolling contact a series of longitudinally disposed bobbins 25. To each of

the shafts 1 and 2 and adjacently one end thereof is secured a pinion 3, an idler 4 being positioned between the two pinions of the pair of shafts, so that the latter both rotate in the same direction. A suitably mounted pinion 5 intermeshes with one of the pinions 3, Figure 5, and also intermeshes with a gear 6 secured to a shaft 7, the gear 6 directly driving one of the pinions, designated as 3', Figures 1 and 5, so that the directions of rotation of the respective bobbins 25 are as shown in said Figure 5. Also secured to said shaft 7 is a friction disc 8 adapted to be rotated by means of frictional contact with a disc 16 secured to the top of a vertically disposed shaft 17. To the bottom of said shaft 17 is secured a bevel gear 18 intermeshing with a bevel gear 19 secured to the end of a horizontally disposed shaft 20. Adjacently the other end of said shaft 20 are mounted tight and loose pulleys 21 and 22, respectively. Power from any suitable source is secured, and applied to the system through the medium of said pulleys 21 and 22.

Mounted upon each of the shafts 1 and 2 are a series of pairs of raised cylindrical surfaces or rollers 23 and 24 having exterior flanges 23' and 24'. The bobbins 25 rest upon said cylindrical surfaces 23 and 24, each bobbin resting upon two pairs of said surfaces, as plainly shown in Figure 1. The bobbins when filled are thus easily removed and replaced. The body of thread 26, shown in Figures 1 and 4, represents the condition when a bobbin 25 is wound about half full of the viscose thread 27 received by a porcelain guide 28 from a second guide 29 positioned in and extending from a trough 60 containing the usual precipitating bath. The viscose solution is expressed from the nozzle 30 into the bath contained in the trough 60 where it is precipitated and solidified into the thread 27.

In order that the thread may be wound longitudinally of the bobbin 25, I provide means for reciprocating the delivered end of the thread longitudinally of said bobbin. This is accomplished through the medium 100 of a reciprocating bar 31 upon which the porcelain guides 28 are mounted. This bar

31 is provided with a pin 32 received by a yoke end 33 of an arm 34 provided with the hub portion 35' secured to a transverse shaft 35. As hereinafter fully described, 8 the pin 32 is secured to a handle 56 pivoted upon the bar 31. Also secured to said hub portion 35' is a downwardly extending arm 36 formed with brackets 37 supporting an externally threaded member 38. A casting 10 39 may be reciprocated vertically upon the screw 38 by the means hereinafter fully described. Secured to this casting 39 is a link 40 whose other end is pivotally connected to one end of a transversely extending arm 15 40', Figure 1, which is pivoted at its other end to the frame of the machine, part of the means forming said pivotal connection between the link 40 and the arm 40' consisting of a rounded end portion 40² upon the 20 arm 40' by means of which the arm 40' may be moved longitudinally of the other end of the link 40, for a purpose hereinafter fully described. Mounted intermediate of the 25 ends of the arm 40' is a flanged roller 42 adapted to ride upon a face cam 43 secured to the power shaft 20, said roller being held to position by a spring 44, Figure 4. It is 30 evident that the apparatus so far described will provide means for rotating the bobbins 25 by fractional contact and for winding the thread 27 longitudinally of said bobbins. The arrangement is such, as plainly shown 35 in Figures 1 and 4, that a very small number of rotations of the shafts 1 and 2 takes places during a single reciprocation of the bar 31, so that the thread 27 is wound upon the bobbin 25 with comparatively large open spaces between adjacent turns of the thread.

40 As is plainly apparent in Figures 1 and 4, the thread 27 is so wound upon the bobbin 25 as to provide at each end of the body 26 of thread a beveled edge 26'. This is to insure the integrity of the wound thread 45 against unraveling and is attained by the following means, altho claims to the same do not form any part of this application but are included in my pending application Serial No. 329,471, upon traverse mechanism for winding machines, of which the subject matter 50 of this application is a division. This application Serial No. 329,471 has resulted in U. S. Patent No. 1,425,655.

Secured to the bottom of the screw member 55 38 is a ratchet 45. At each reciprocation of the link 40 this ratchet 45 is adapted to strike a rigid stop 46 so as to slightly turn the ratchet 45. It will be noted that the vertically movable casting 39 is intersected by 60 a pair of blocks 47. These blocks are the only members that have threaded engagement with the screw 38 and are held to such threaded engagement by a spring 48. The result is that the casting or crosshead 39 is 65 fed downwardly slightly each time the

ratchet 45 strikes the stop 46 to shorten up the stroke of the bar 31 upon which the porcelain guides 28 are mounted. Whenever it is desired to return the crosshead 39 to the top of the screw member 38 to start a new 70 stroke, after one bobbin 25 has been fully wound, the spring 48 is loosened manually to release the blocks 47 from the screw member 38 and the crosshead 39 shoved up to the proper position by means of a handle 49. 75

It is evident that, due to the increasing diameter of the body of thread 26, more thread 27 will be wound upon the bobbin at each turn of the bobbin. In order to compensate for this tendency to increase the pull 80 upon the thread, I provide means for constantly slowing up the speed of the shafts 1 and 2. Generally, this is accomplished by a change in the position of the friction disc 8 upon the friction disc 16 at each turn of the 85 shaft 20. The detail of this arrangement consists of the following means.

Loosely mounted upon a sleeve 10 rotatably mounted upon the shaft 7 is a bell-crank having arms 11 and 11'. Secured to the arm 90 11 by a suitable pin is a pawl 13. This pawl co-operates with the ratchet 14 fixed by any suitable means to the sleeve 10 and fixing longitudinally of the shaft 7 a shoulder 9 of the friction disc 8 which is secured by a running fit in a suitable groove formed in the sleeve 10. This sleeve member 10 is formed with a peripheral screw threaded portion adapted to co-operate with internal screw threaded portions of a pair of blocks 51 intersecting a rigid boss 50 secured to a bracket 15 in which one end of the pairs of shafts 1 and 2 are mounted. These blocks 51 are held to engagement with the sleeve 10 by means of a spring 52, Figure 3. The other arm 11' 105 of the bell-crank is secured to the top of a vertically disposed eccentric rod 53 which in turn is secured at its lower end to an eccentric strap 54 secured to the driving shaft 20. It is evident that each rotation of the driving shaft 20 will result in a feeding of the sleeve 10 through the nut 50 and consequently in a movement of the friction disc 8 toward the center of the friction disc 16, thus 110 slowing up the speed of rotation of the shaft 7 and consequently of the roller shafts 1 and 2. In order that the highest rate of speed of the shafts 1 and 2 may be secured at the time of the winding upon a new bobbin, the sleeve 115 10 is relieved from the blocks 51 by means of releasing manually the spring 52, and the friction disc 8 and shaft 7 pushed to the right, Figure 2, by means of a handle 55, the locking pin 55' sliding in the annular recess 7² formed around an intermediate reduced portion 7³ of the shaft 7.

120 It will be noted in Figure 1 that adjacent longitudinal pairs of the rollers 23 and 24 are not utilized at the same time but that the bobbins 25 are mounted on alternate 125 130

pairs. The result is that when the bobbin mounted upon one pair of said rollers is full wound, the bar 31 is shifted longitudinally the desired amount to bring the guides 28 adjacently the alternate bobbins. This is accomplished by the following means, which, however, are particularly claimed in said pending application, Serial No. 329,741.

A handle 56, Figure 4, is pivoted to the bar 31 at one end upon a pin 57 and detachably locked at the other end by a pin 56². The latter is released from the bar 31 and the handle is turned upwardly so as to release the pin 32 from the yoke 33 and the said bar 31 then manually shoved longitudinally until the pin 57 lies in the former position of the pin 56² when, by lowering the handle and locking the pin 56² in the position 56', the pin 32 again registers with the yoke 33 and the guides 28 are disposed adjacently the alternate bobbins 25.

It will be evident from the accompanying drawings that only one unit of my improved bobbin winding mechanism and speed control therefore has been described and that the entire machine consists of a multiplicity of said units, two or more pairs of shafts 1 and 2 being operated simultaneously by means of multiple arms 34 and 34', multiple pinions 3 and other necessary multiple parts.

What I claim is:—

1. In bobbin winding mechanism and speed control therefor, the combination of a driving member; means furnishing a thread; a bobbin upon which the thread is to be wound; rotatable means connected to said driving member, said bobbin being turned by said rotatable means; and means positively actuated by the driving member and acting directly upon said rotatable means automatically to change the relative speed ratio of said rotatable means and said driving member at predetermined intervals.

2. In bobbin winding mechanism and speed control therefor, the combination of a driving member; means furnishing a thread; a bobbin upon which the thread is to be wound; rotatable means connected to said driving member, said bobbin being turned by said rotatable means; and means positively actuated by the driving member and acting directly upon said rotatable means automatically and at each turn of said driving member to decrease the speed of said rotatable means.

3. In bobbin winding mechanism and speed control therefor, the combination of a driving member; means furnishing a thread; a bobbin upon which the thread is to be wound; a friction disk; means connecting said driving member to said disk to rotate the latter; a second friction disk adapted to be rotated by said first disk; means connecting said second friction disk to said bobbin to turn the latter; and means inde-

pendently and positively actuated by said driving member to shift said second friction disk periodically.

4. In bobbin winding mechanism and speed control therefor, the combination of a driving member; means furnishing a thread; a rotatable bobbin upon which the thread is to be wound; means connecting said driving member to said bobbin including a pair of friction disks; and means automatically and periodically decreasing the speed of said bobbin and including a sleeve suitably rotatably mounted, said sleeve being formed with a threaded peripheral portion and being longitudinally fixed relatively to said disk, longitudinally fixed internally threaded blocks co-operating with the threaded portion of said sleeve, a ratchet secured to said sleeve; and a pawl co-operating with said ratchet and adapted to be actuated by said driving member.

5. In bobbin winding mechanism and speed control therefor, the combination of a driving member; means furnishing a thread; a rotatable bobbin upon which the thread is to be wound; means connecting said driving member to said bobbin including a pair of friction disks; and means automatically and periodically decreasing the speed of said bobbin and including a longitudinally movable sleeve suitably rotatably mounted, said sleeve being formed with a threaded peripheral portion and being longitudinally fixed relatively to said disk, longitudinally fixed internally threaded blocks co-operating with the threaded portion of said sleeve, resilient removable means holding said threads in engagement by pressure upon the periphery of said blocks, which pressure may be manually relieved to release the threads, a ratchet secured to said sleeve; and a pawl co-operating with said ratchet and adapted to be actuated by said driving member.

6. In bobbin winding mechanism and speed control therefor, the combination of a driving member; means furnishing a thread; a rotatable bobbin upon which the thread is to be wound; means connecting said driving member to said bobbin including a pair of friction disks; a suitably supported shaft to which one of said disks is rotatably secured, said shaft forming part of the means connecting said driving member and said bobbin; a sleeve rotatably mounted upon said shaft, said disk being fixed longitudinally of said sleeve and rotatable relative to the latter; and means periodically moving said sleeve longitudinally of said shaft.

7. In a bobbin winding mechanism and speed control therefor, the combination of a driving member; means furnishing a thread; a rotatable bobbin upon which the thread is to be wound; means connecting

said driving member to said bobbin including a pair of friction disks; a suitably supported shaft to which one of said disks is rotatably secured, said shaft forming part of the means connecting said driving member and said bobbin; a sleeve rotatably mounted upon said shaft, said disk being fixed

longitudinally of said sleeve and rotatable relative to the latter; and means automatically moving said sleeve longitudinally of 10 said shaft at each turn of the driving member.

Signed by me this 8th day of May, 1922.
CHARLES A. HUTTINGER.
